UNITED STATES PATENT OFFICE.

JAMES J. MURDOCH, OF DETROIT, MICHIGAN, ASSIGNOR TO DWIGHT LUMBER CO., OF DETROIT, MICHIGAN, A CORPORATION OF MICHIGAN.

MECHANISM FOR MANUFACTURING PARQUETRY FLOORING.

No. 921,618.

Specification of Letters Patent.

Patented May 11, 1909.

Application filed July 15, 1907, Serial No. 383,750. Renewed October 3, 1908. Serial No. 456,014.

To all whom it may concern:

Be it known that I, JAMES J. MURDOCH, a citizen of the United States, residing at Detroit, in the county of Wayne and State of Michigan, have invented certain new and useful Improvements in Mechanism for Manufacturing Parquetry Flooring, of which the following is a specification.

My invention is designed to provide mechanism for manufacturing flexible parquetry flooring or wood carpeting from separable strips of wood. For convenience of handling parquetry flooring constructed of multiple pieces of wood, it is well known, that the 10 pieces of wood constituting the flooring, or wood carpeting are usually assembled in a form, and when properly arranged, the pieces constituting the pattern are held tightly together, and coated on the bottom 15 surface thereof with glue or other suitable adhesive substance, a fabric being spread and secured upon the glued surface of the strips, the pattern then being set to dry.

The object of my present invention is to 20 provide machinery for assembling and securing together the separable pieces constituting a given form or pattern of the flooring or carpeting. I accomplish my object as hereinafter described and claimed and illustrated in the accompanying drawings, in which,

Figure 1 is a view in perspective illustrating features of my invention. Fig. 2 is a view in vertical longitudinal section. Fig. 3 25 is a view in cross section.

The aim of my invention is to accomplish the above desired results in a simple, economical and superior manner.

In the drawings *a* represents any suitable 30 support upon which is journaled a driving shaft *b* provided with a pinion *c* meshing with a gear *d* upon a driven shaft *e*, upon which are mounted one or more eccentrics *f*. A feeding chute or runway is indicated at *g* to contain the strips *h* which are to be assembled. The feeding runway or hopper is located at one extremity of guide-ways or grooved tracks *i* upon each side of the machine upon which the extremities of the strips *h* may 35 rest and be automatically moved forward by a pusher bar *j* connected with said eccentrics, as by connecting rods *k*. The pusher bar *j* contacts with the lower strip *h* in the run-way, and at each revolution of the driven shaft *e*, the strips are moved forward one by

one from the runway upon said grooved tracks, thereby moving forward all preceding strips upon the tracks simultaneously. Underneath the tracks, and forward of the feeding runway, is a roller *l* revolving in a glue 63 pot or chamber *m* by means of which glue or other suitable adhesive substance is applied to the under surface of the strips *h*, as they are moved forward. A roll or spool of suitable cloth or other fabric is indicated at *n* located beneath the tracks, the fabric when unwound from its spool preferably passing over a tension roller *p*, and over a contact roller *q*, whereby the fabric is brought firmly into contact with the glued under surfaces 70 of the strips and caused to adhere thereto. In advance of the contact roller *q* are one or more friction brushes *r* or similar instruments by which the fabric is smoothed out and pressed firmly in place on the under surface of the strips. 75

The pressure of the adhesive roller *l* may be effected in any suitable manner, as by a weight *s* upon a cranked end of the roller, the tension of the brushes *r* being also made adjustable, as by a weight *t* upon an arm *u* upon which the corresponding brush is engaged. Forward of the tension brushes *I* prefer to form underneath the tracks a drying chamber *v*, into which steam pipes *w* may 80 extend, a blast apparatus being also preferably provided for said chamber, which may consist of a pipe *x* entering said chamber, said pipe connected with a blower *y*. The extremities of the tracks are preferably 85 curved, as shown in Fig. 1, so that the strips to which the fabric has been glued will be discharged from the tracks upon a table indicated at *z*, the reverse side upward. An attendant then simply cuts the fabric transversely between any two adjacent strips, leaving as many pieces or strips as may be desired for a single pattern or form assembled. The strips thus being separable one 90 from another in the completed flooring enables this severing to be made at any desired point. The curvature of the tracks should be of sufficient length so that the completed flooring shall be discharged therefrom, the cloth side uppermost, in order that 95 the workman may separate the strips at any desired point with a knife drawn between any two adjacent strips to form various sections or patterns as may be desired.

To hold the strips firmly down upon the 110

tracks and so that their adjacent edges shall be pressed so tightly together so that no glue shall be spread upon their adjacent edges any suitable means may be employed, as for example, angle irons or pressure shoes 4 located above the extremities of the strips to hold the extremities of the pieces firmly down upon the tracks. A friction clamping bar 7 is also secured above the pieces intermediate the extremities thereof, said bar being held in place by transverse bars 8. Beneath the pieces of wood toward the forward end of the machine, I prefer, also, to provide a friction clamping device to exert a friction tension upon the strips, a clamping bar 9 being shown bearing against the strips from beneath, intermediate the extremities thereof. The pressure bar 7 preferably extends directly from the feeding chute or hopper *g* over and beyond the means for applying the adhesive substance, so that the separable strips or pieces of wood will be sufficiently retarded in their forward movement by the pressure mechanism to cause the advancing mechanism to maintain the adjacent edges of the successive strips in close and firm contact, thereby preventing the penetration of the adhesive substance between the edges of the successive strips.

It will be seen that the means for applying the adhesive substance to the under surface of the strips is located below the pressure bar 7. It will be evident also, that the means for applying the fabric to the under surface of the strips is located to perform its function after the application of the adhesive substance.

In Fig. 2, I have shown means for signaling whenever a roll of fabric gives out. This may be done in any suitable manner, as by a swinging arm 5, one extremity of which rests upon the fabric. When a roll of fabric has been exhausted, the arm 5 will drop, suitable electric mechanism 6 being provided with which the arm 5 forms electrical contact, thereby signaling the attendant.

It will be seen that only two attendants are required in connection with the machine, one to supply the hopper or feeding chute with strips or pieces to be assembled, and another to sever the work at the table *z*. The tracks may obviously be of any desired length, the object being to have them of sufficient length to effectually dry the glued fabric upon the strips before it reaches the table *z*, with or without the heating or drying chamber.

The operation of the device will now be thoroughly understood, and need not be further explained.

What I claim as my invention is:

1. In a machine for assembling separable strips of flexible parquetry flooring, the combination of a frame, a track at each side of the machine upon which the ends of the strips

are carried, a feeding chute located at one end of the tracks, mechanism to advance the strips one by one from the bottom of the feeding chute in a flat or horizontal position upon the tracks, means underneath the tracks to apply an adhesive substance or coating to the under surfaces only of said strips as they are advanced, means to apply a fabric to the separable surfaces of the strips after the adhesive substance has been applied, means to press the fabric firmly in place on the under side of the separable strips, and pressure means bearing against said strips to hold the edges of said strips firmly in contact, so that the strips will be sufficiently retarded by the pressure means to cause the advancing mechanism to press and maintain the successive strips in close contact with each other and thereby prevent the penetration of the adhesive substance between the edges of the successive strips, the means for applying the adhesive substance being located beneath the pressure means, and the pressure means above the strips extending directly from the feeding chute past the means for applying the adhesive substance.

2. In a machine for assembling separable strips of flexible parquetry flooring, the combination of a frame, a track at each side of the machine upon which the ends of the strips are carried, a feeding chute located at one end of the tracks, mechanism to advance the strips one by one from the bottom of the feeding chute in a flat or horizontal position upon the tracks, means underneath the tracks to apply an adhesive substance or coating to the under surface only of said strips, and means to attach a fabric to the coated surface of the separable pieces, said tracks being curved at the extremity thereof opposite the feeding chute to discharge the flexible flooring with the reverse side upward.

3. In a machine for assembling separable strips of flexible parquetry flooring, the combination of a frame, a track upon each side of the frame upon which the ends of the strips are carried, a feeding chute located at one end of the tracks, mechanism to advance the strips one by one from the bottom of the feeding chute in a flat or horizontal position upon the tracks, means underneath the tracks to apply an adhesive substance or coating to the under surface of said strips, means to apply a fabric to the coated surface of the strips, and means located above and beneath the strips to hold the separable strips down upon the tracks and to hold the edges of said strips firmly in contact so that the strips will be sufficiently retarded by the pressure means to cause the advancing mechanism to press and maintain the successive strips in close contact with each other and thereby prevent the penetration of the adhesive substance between the edges of the strips.

successive strips, the means for applying the adhesive substance being located beneath the pressure means, and the pressure means above the strips extending directly from the 5 feeding chute past the means for applying the adhesive substance.

4. In a machine for assembling separable strips of flexible parquetry flooring, the combination of a frame, a track at each side of 10 the machine upon which the ends of the strips are carried, a feeding chute located at one end of the tracks, mechanism to advance the strips one by one from the bottom of the feeding chute in a flat or horizontal 15 position upon the tracks, means underneath the tracks to apply an adhesive substance or coating to the under surface only of the strips, and means to apply a fabric to the coated surfaces of the strips, said tracks 20 curved at their discharge ends to discharge the work with the fabric uppermost, and pressure means bearing upon said strips to hold the strips down upon the track and to hold the edges of the strips in firm contact, 25 the means for applying the adhesive substance being located beneath the pressure means.

5. In a machine for assembling separable strips of flexible parquetry flooring, the combination of a frame, tracks at the sides of the 30 frame upon which the ends of the strips are carried, a feeding chute at one end of the track, means to advance the strips from the bottom of the feeding chute in a flat or horizontal 35 position upon the tracks, means underneath the tracks to apply an adhesive substance or coating to the under surfaces only of said strips, means to apply a fabric to the coated surfaces of the strips, pressure 40 means midway said tracks, and transverse bars engaged at their extremities with the opposite sides of the frame to hold the pressure means in place, said pressure means exerting pressure upon the strips to hold the 45 edges of the strips in firm contact, the means for applying the adhesive substance being located beneath the pressure bar, the pressure bar extending from the feeding chute past the means for applying the adhesive 50 substance.

6. In a machine for assembling separable strips of flexible parquetry flooring, the combination of a frame, a track at each side of the frame, a feeding chute, mechanism to advance the strips from the feeding chute upon 55 the tracks, means to apply an adhesive substance or coating to the under surfaces only of said strips, means to exert a tension upon said mechanism, a contact roller to apply a fabric to the coated surfaces of the strips, means to exert a tension upon said contact roller, pressure means bearing upon the strips to hold the edges of the strips tightly together at the front of the machine, a contact brush by which the applied fabric is 60 65

pressed firmly in place, and means to exert a tension upon said brush, the means for applying the adhesive substance being located beneath the pressure bar, the pressure bar extending from the feeding chute past the 70 means for applying the adhesive substance.

7. In a machine for assembling separable strips of flexible parquetry flooring, the combination of a support provided with a track at each side thereof, upon which the extremities of the strips are carried, a driving shaft journaled upon the support, a pinion upon said shaft, a driven shaft provided with a gear meshing with said pinion, a feeding chute located at one end of the tracks, a pressure bar eccentrically connected with said gear to move forward the strips one by one from the base of said chute upon said tracks, means underneath the tracks to apply an adhesive substance or coating to the 85 under surfaces only of said strips as they are advanced upon the tracks, means to apply the fabric to the separable coated surfaces of the strips, and pressure means to hold the edges of the separable strips firmly together 90 upon the tracks, the means for applying the adhesive substance being located beneath the pressure bar, the pressure bar extending from the feeding chute past the means for applying the adhesive substance. 95

8. In a machine for assembling separable strips of flexible parquetry flooring, the combination of a frame, a track at each side of the machine upon which the ends of the strips are carried a feeding chute, mechanism to advance the strips one by one from the bottom of the feeding chute in a flat or horizontal position upon the tracks, means underneath the tracks to apply an adhesive substance or coating to the under surfaces 100 only of said strips as they are advanced, means to apply a fabric to the separable surfaces of the strips after the adhesive substance has been applied, and means to press the fabric firmly in place on the under side of 105 the separable strips.

9. In a mechanism for assembling separable strips of flexible parquetry flooring, the combination of a frame, a track at each side of the machine upon which the ends of the strips are carried a feeding chute located at one end of the tracks, mechanism to advance the strips one by one from the bottom of the feeding chute in a flat or horizontal position upon the tracks, means underneath the 115 tracks to apply an adhesive substance or coating to the under surfaces only of said strips as they are advanced, means to apply a fabric to the separable surfaces of the strips after the adhesive substance has been 120 applied, means to press the fabric firmly in place on the under side of the separable strips and pressure means bearing against said strips to hold the edges of said strips 125 firmly in contact so that the strips will be 130

sufficiently retarded by the pressure means to cause the advancing mechanism to press and maintain the successive strips in close contact with each other and thereby prevent the penetration of the adhesive substance between the edges of the successive strips, the means for applying the adhesive substance being located beneath the pressure means, and the pressure means above the strips extending directly from the feeding

chute past the means for applying the adhesive substance, and mechanism to indicate the exhaustion of the fabric.

In testimony whereof I affix my signature in presence of two witnesses.

JAMES J. MURDOCH.
